(57) CLAIM

The ornamental design for an infrared motion detector, as shown and described.

DESCRIPTION

FIG. 1 is a perspective view of an embodiment of the present invention;

FIG. 2 is a top view of the embodiment of the present invention;

FIG. 3 is a front view of the embodiment of the present invention;

FIG. 4 is a back view of the embodiment of the present invention;

FIG. 5 is a side view of the embodiment of the present invention (with the opposite side view being a mirror image of this side view);

FIG. 6 is a bottom view of the embodiment of the present invention; and,

FIG. 7 is a schematic drawing of a door, in broken lines, showing one of many different possible utilizations of the embodiment of the present invention as shown in FIG. 1.
